(57) **CLAIM**

The ornamental design for a kitchen appliance receptacle, as shown and described.

DESCRIPTION

FIG. 1 is a front view of a kitchen appliance receptacle.

FIG. 2 is a left side view thereof.

FIG. 3 is a right side view thereof.

FIG. 4 is a rear view thereof.

FIG. 5 is a rear perspective view thereof.

FIG. 6 is a front perspective view thereof.

FIG. 7 is a bottom view thereof.

FIG. 8 is a top plan view thereof;

FIG. 9 is an in use front perspective view thereof; and,

FIG. 10 is an in use rear perspective thereof.

The characteristic feature of the design resides in the shape and configuration of the annulus of the receptacle. The vessel shown in phantom lines in FIGS. 9 and 10 illustrates one possible vessel for use with the receptacle but forms no part of the claimed design.

The broken lines in the drawings are included for the purpose of illustration and form no part of the claimed design.
